Company, Inc., Bridgeport, Conn., a corpora-
tion of Delaware

Application June 25, 1943, Serial No. 492,254

6 Claims. (Cl. 42—1)

This invention relates, in general, to firearms, and, in particular, to a grenade launcher adapted to be used on an automatic gas operated rifle of the type illustrated in the Garand patent, No. 2,287,032.

An object of the invention is to launch a grenade from the rifle barrel using the pressure of powder gases transmitted entirely through the barrel. A further object is to provide an automatic gas operated rifle with a grenade launcher which is secured to the end of the rifle barrel by clamping the launcher to the rear edge of the front sight mounting. A still further object is to adapt an automatic gas operated firearm for launching grenades by providing the gas cylinder with a gas valve which is automatically held open by the grenade launcher when the latter is secured on the end of the rifle barrel.

Other objects, features and advantages of the invention will be more fully described in the following specification which is descriptive of an exemplary embodiment of the invention. It will be understood, however, that the invention may be modified within the scope of the appended claims for use with firearms of other types than that shown in the drawings.

In the drawings:

Fig. 1 is a side elevation partly in section of the grenade launcher of this invention secured on the end of a rifle barrel.

Fig. 2 is a plan view in section of the launcher shown in Fig. 1.

Fig. 3 is a plan view in section of the launcher showing a grenade supported thereon.

Fig. 4 is an end elevation of the launcher on line 4—4 of Fig. 1 showing the clamp in elevated position.

Fig. 5 is a sectional plan view of the gas valve and adapter on line 5—5 of Fig. 1.

Fig. 6 is a perspective view of one of the straps having the clamp thereon.

Fig. 7 is a sectional side elevation of the friction cup of the launcher.

Fig. 8 is an end view of a gas cylinder valve screw for use in the gas cylinder of a firearm mounting the launcher.

Fig. 9 is a side elevation in section of the valve screw shown in Fig. 8.

Fig. 10 is an end view of a modification of the gas valve shown in Fig. 8.

Fig. 11 is a side elevation in section of the modified gas valve screw.

Fig. 12 is a perspective view of a modified form of grenade launcher.

Fig. 13 is a plan view of a modified type of strap for connecting the launcher to the rear edge of the front sight.

Referring to Fig. 1, the grenade launcher of this invention is shown mounted on the barrel 15 of a firearm which, for the purposes of illustration, is of the type described in the above identified Garand patent and comprises a gas cylinder 16 provided with an integral rear band 17 and a front band 18, whereby the cylinder is supported on the underside of the barrel. A suitable retaining member 19 is shown threadedly secured on the front or muzzle end of the barrel and is adapted to abut the front edge of the band 18 of the gas cylinder so as to hold the band in place on the barrel. The band 18 is located adjacent a gas port 20 of the barrel and is provided with a gas inlet 22 which is in alignment with the gas port 20. Normally, a standard gas cylinder lock screw (not shown) is mounted through an aperture 23 of the retaining member 19 and is threaded in the front end of the gas cylinder to form both a removable closure therefor and a coupling for connecting the end of the cylinder to the retaining member 19.

In the present invention, however, the lock screw is not used and a suitable gas cylinder valve screw is substituted therefor which serves both as a coupling for the gas cylinder and retaining member and as means for enabling the escape of gas from the barrel in the manner and for the purposes hereinafter described.

The front band 18 constitutes a mounting for a front sight, indicated generally at 24, the latter being secured to the band 18 by a dove-tail connection comprising a transversely disposed dove-tail tongue 25 and slot 26 adapted to receive complementary parts of the front sight.

The improved grenade launcher, indicated generally at 27, is adapted to be readily mounted without the use of tools on the muzzle end of the barrel 15 for supporting a grenade. As shown generally in Figs. 1 and 3, the grenade is typical of a new type developed by the Ordnance Department and comprises a hollow cylindrical tail 28

attached at one end to the container 29 of the explosive charge and having suitable guide vanes 30 at its opposite end.

It will be understood that, when a bullet is shot from the barrel, the gas pressure behind the bullet does not escape into the gas port to act on the auto slide mechanism until the gas port has been uncovered by the bullet and then the pressure is only of momentary duration. Similarly with the old types of grenades, the stem of the grenade covered by the gas port until the grenade was substantially clear of the muzzle end of the barrel. However, the newest type of grenade embodies simply a hollow cylindrical tail portion 28 having a wall or partition 32 adjacent its forward end. When launching this type of grenade from the rifle, the wall 32 of the grenade covers the barrel muzzle, and, consequently, the powder gases which are developed in the barrel prior to discharge of the grenade escape through the gas port and act for a relatively long period of time on the slide actuating mechanism. It has been found that subjecting the slide action mechanism to these hot gases for the longer periods effect greater wear and strain on the mechanism and is hazardous. The grenade launcher 27 of this invention provides means for overcoming these malfunctions.

Referring to Fig. 2, the improved launcher comprises a relatively heavy walled cylindrical tube 33, the internal diameter of which corresponds to or may be slightly greater than the bore of the barrel 15 and which has a counterbore 34 in its rear end of a diameter to receive the muzzle of the rifle; and shoulder 35 adapted to abut the end of the muzzle as hereinafter described.

The exterior surface of the tube is provided adjacent its rear end with a relatively low annular shoulder 36 formed by turning or grinding a relatively narrow band 37 of slightly less diameter than the original diameter of the tube. This band 37 terminates forwardly in a second annular shoulder 38 which is formed by further reducing the diameter of the tube throughout the remainder of its length. The external diameter of the reduced portion 39 thus formed is comparable to the diameter of the rifle barrel and is provided adjacent its forward end with an annular shoulder 40 and corresponding neck portion 42 of reduced diameter. A circumferential groove 43 is cut or otherwise formed in the neck 42 at the extreme forward end of the tube.

Mounted to make a smooth longitudinally sliding fit on the tube 33 is a cylindrical sleeve 44. To this end, the internal diameter of the sleeve 44, at its rear end, is substantially equal to the exterior diameter of the corresponding portion of the tube 33. Moreover, the internal diameter of the sleeve remains the same from the rear end of the sleeve forwardly to a point therein which is normally substantially opposite the center of the annular band 37 of the tube 33. At this point, the internal diameter of the sleeve is decreased by an amount corresponding substantially to the depth of the band 37 so as to form an internal shoulder 45 in the sleeve which is normally located forwardly of the shoulder 36 of the tube 33 to enable the sleeve to move rearwardly relative to the tube, but which is adapted to abut the shoulder 36 to limit the relative movement of the sleeve and tube as hereinafter described. From the shoulder 45, the internal diameter of the sleeve remains constant throughout a major portion of its length, but terminates ad-

jacent the forward end of the sleeve in a shoulder 46 substantially equal in height to the height of the shoulder 38 of the tube 33. The shoulder 46 is formed by an annular restriction 47 of the sleeve adapted to slidably engage the adjacent reduced portion 39 of the tube 33. As shown in Fig. 2, there is thus formed an annular closed space 48 having end walls defined by the annular shoulders 38 and 46 of the tube and sleeve respectively.

The sleeve and tube are adapted to be maintained in normal relationship by means of a coil spring 49 which is supported on the tube 33 within the annular space 48 and abuts at its opposite ends the shoulders 38 and 46 of the tube and sleeve respectively to hold the respective shoulders 36 and 45 in normal spaced relationship, as shown in Fig. 2. It will be clear, however, that, due to the clearance space between the shoulders 36 and 45, the sleeve may be moved rearwardly on the tube 33 a distance corresponding substantially to the width of the annular space between these shoulders.

The rear end of the sleeve 44 is formed integrally with a yoke member 52 which comprises a substantially rectangular relatively thick plate having rectangular recesses 53 cut in each side to provide bearing elements 54 of a hinge joint. A hole 55 is drilled vertically through each pair of bearing elements to receive a hinge pintle 56. Mounted in each recess 53 between the bearing elements 54 is the eye portion 57 of a strap 58 which is pivotally secured to the yoke by a hinge pintle 56.

Each strap comprises a flat strip of metal substantially U-shaped in cross section provided at its rear end with a block 59 which is welded or otherwise fastened in the channel portion of the strap and has a longitudinally disposed semi-cylindrical surface 60 on its inner face conforming substantially to and adapted to embrace the side of the rifle barrel.

The forward edge 62 of each block is suitably bevelled, as shown in Fig. 2, to engage the rear edge of the front sight base or mounting 18 when the straps 58 are closed, as shown in Figs. 2 and 4. Each strap is provided on its upper surface immediately above its barrel embracing block 59 with a substantially flat laterally extending lip 63 and 63' respectively, the lip 63 being adapted to overlie and frictionally engage the lip 63' when the straps are closed, see Fig. 4. The forward edges 630 and 630', respectively, of each lip constitutes, in effect, a cam surface which is adapted to cammingly engage behind the rear edge of the front sight mounting so as to draw the straps 58 and yoke 52 rearwardly with respect to the barrel, thereby fastening the launcher 27 onto the muzzle end of the gun and taking up any tolerance between the end of the muzzle and the rear edge of the front sight as hereafter described.

Suitable means for locking the straps 58 in closed position is shown in Fig. 6 and comprises a clip 64 which is pivotally secured at one end to one of the straps 58 and is formed at its opposite end with a U-shaped clasp 65 adapted to be swung down over the hook-shaped ends or lips of the closed straps to hold them securely together.

From the foregoing description, it will be clear that the launcher 27 is mounted on the gun barrel by inserting the muzzle end of the barrel 15 into the counterbore 34 of the tube 33 and 75 thereafter swinging the straps 58 together, as

shown in Fig. 2, to cammingly engage the front edges 630 and 630' thereof with the rear edge of the front sight mounting.

As the straps are squeezed together, the camming action resulting from engagement of the camming surfaces 630 and 630', with the rear edge of the front sight, draws the yoke 52 and its sleeve 44 rearwardly relative to the tube 33 against the compression force of the coil spring 49. Means are thus provided for drawing the shoulder 35 of the tube 33 tightly into contact with the muzzle end of the barrel. This is an important feature inasmuch as when launching grenades the gas pressure acting on the front of the launcher tends to drive it rearwardly against the end of the barrel; moreover, when firing bullets through the launcher, the recoil force tends to pull the launcher forward against the rear edge of the front sight mounting. By providing the above described resilient mounting, each launcher can thus be securely fastened to a gun muzzle despite tolerances between the end of the muzzle and the rear edge of the front sight. The hook portions 63 and 63' of the straps 58 are locked together behind the rear edge of the front sight mounting as above described, the recoil load being taken by engagement of the front edges 62 of the blocks 59 with the rear edges of the front sight.

Suitable means is provided on the front end of the launcher for releasably retaining the grenade on the sleeve 44 for all elevations of the barrel and comprises a friction cup 66 which, as shown in Fig. 7, is apertured as at 67 to form a sliding fit on the reduced portion 39 of the tube 33 adjacent the shoulder 40 and is provided at its rear end with resilient circumferentially spaced fingers 68, four being shown in the present embodiment, which are sprung outwardly slightly so as to frictionally engage the sleeve 28 of the grenade. The friction cup is adapted to abut the shoulder formed by the end 44' of the sleeve 44. A retaining ring 69 is carried on the reduced portion 42 of the tube 33 and abuts the shoulder 40 thereof, being locked in position by a snap ring 70 which is engaged in the groove 43 of the tube within a counterbore 72 in the front end of the ring 69. Since the outside diameter of the ring 69 is substantially equal to the diameter of the sleeve, the gas pressure developed in the barrel when projecting grenades is transmitted by the ring 69 to the tube 33 and hence to the end of the rifle barrel and substantially none of the gas pressure is enabled to act against the shoulder 44' of the sleeve 44.

Suitably secured to the yoke 52 is a means constructed and arranged to engage and open a valve screw of the type hereinafter described when the launcher is fastened onto the end of the barrel. The valve screw opening means comprises a cylindrical stem 73, see Fig. 5, having a drive fit in a centrally located aperture 74 of the yoke 52 and provided with an enlarged rearwardly extending head 75.

Secured to the yoke by the stem 73 is an adapter 76. The latter provides means for preventing the shooter from attaching the launcher to a firearm from which the standard gas cylinder lock screw has not been removed and comprises a substantially rectangular block, the longitudinal axis of which is substantially transverse to the longitudinal axis of the barrel and parallel to the horizontal plane of the barrel. The front face of the adapter abuts the rear face of the

yoke and is held in engagement therewith by a shoulder 77 of the stem 73 which engages the bottom 78 of a recess 79 formed in the rear face of the adapter.

5 The recess 79 is substantially rectangular except that its right and left sides 80 and 82, see Fig. 4, are concave arcs of a circle, the diameter of which is greater than the height of the block and substantially equal to the outside diameter of the gas cylinder valve screw hereinafter described. Moreover, the recess 79 is counterbored as at 83 to provide a means for guiding the adapter 76 into place.

The gas cylinder valve screw is, as shown in Figs. 5, 8 and 9, adapted to be provided as standard equipment or substituted for the standard lock screw used on the above identified rifle when equipping the gun with the grenade launcher. Further, it should be pointed out that, when the gun is equipped with the gas cylinder valve screw, the launcher of this invention may be quickly mounted for firing a grenade or removed and the gun used in the ordinary manner for firing projectiles without making any other alterations in the gun. Moreover, the bayonet may be mounted on the gun even though the gas cylinder valve screw is in place. The valve screw comprises a bushing 84 suitably dimensioned to fit in the lock screw aperture 23 of the retaining member 19 and is threaded at its rear end to engage in the internally threaded aperture of the front sight mounting 18. The bushing is provided with a rim 85, the diameter of which corresponds to the diameter of the recess 79 of the adapter 76 so as to make a nice fit therein when the launcher is secured to the barrel. By making the diameters of the recess 79 and rim 85 slightly less than the outside diameter of the standard type of lock screw, it will be clear that the launcher cannot be mounted on a rifle which is equipped with the usual type of lock screw.

45 The bushing 84 is provided with a longitudinally drilled bore having a plurality of circumferentially spaced longitudinally extending grooves 86, four being shown in the present embodiment, which form lands 87. The grooves 86 constitute gas escape apertures and are in direct communication with a valve seat 88 which is formed on the rear 50 end of the bushing and provided with an annular relief recess 89. The bore is counterbored from the front or rim end of the bushing rearwardly a predetermined distance to form shoulders 90 on the four lands 87. Further, the lands are provided with a second counterbore which terminates in a bevelled shoulder 91 on each land for the purpose hereinafter described.

55 Slidably supported on the lands in the rear part of the bushing is a valve member comprising a cylindrical valve stem 92 having a circumferential groove 93 in its front end and a valve head 94 at its opposite end, the latter having a bevelled surface 95 adapted to make a gas tight fit on the valve seat 88 of the bushing. As shown, the valve seat 88 is relieved by the recess 89 so that, in the event carbon is deposited on the surfaces, it will not keep the valve member from seating correctly. Likewise, the counterbored portions of the bore provide relief surfaces for the valve stem 92.

70 Suitable means for retaining the valve member in the bushing comprises an annular snap ring 96 which is sprung into the groove 93 of the valve stem and is adapted to frictionally engage the counterbored lands 87 and their respective shoulders 90 and 91. One end 97 of the ring is adapted

to project into one of the grooves 86 of the bushing, as shown in Fig. 8, to prevent rotation of the ring.

When the valve is closed, as shown in Fig. 9, the snap ring 86 expands into a frictional contact with the bevelled shoulders 91 and thus effectively holds the valve from jarring open, for it will be evident that any force tending to move the valve stem rearwardly so as to open the valve will be resisted by the force necessary to compress the snap ring as it rides up the bevelled shoulders 91 of the lands. In accordance with this construction, the valve will be held on its seat at all times unless positively opened which occurs when the valve stem is engaged by the above described valve opening stem 73 of the launcher. Further, complete removal of the valve from the bushing is even more strongly resisted by engagement of the snap ring with the square shoulders 99 of the lands. In the normal use of the gun, no forces are developed on the valve stem sufficient to project the valve member from its bushing.

A modification of the valve screw is shown in Figs. 10 and 11 and comprises a bushing 98 substantially identical to the bushing 84, but provided with a bore having a single counterbore forming square shoulders 99 on the lands 100. The valve stem 101 of the valve member is shown provided at its forward end with a small lip or annular square shoulder 102 which is slightly larger in diameter than the diameter of the lands 100 rearwardly of the shoulders 99. The valve is assembled by forcing the stem through the smaller end of the bushing until the shoulder 102 of the stem passes beyond the square shoulder 99 of the lands. Thereupon the shoulder 102 expands or recovers slightly sufficiently to engage the shoulders 99 to prevent the valve member from dropping out of the bushing.

It will be evident, from the above description, that when the launcher is mounted on the rifle barrel in the manner described above, the head 75 of the valve opening stem 73 engages the stem 92 of the valve and moves it rearwardly in its bushing thereby holding the valve head off of its seat 88. The tolerance between the end of the barrel and the valve stem will, of course, be taken up by the resilient mounting of the sleeve 44 on the tube 33.

Fig. 12 shows a modified form of strap which may be used with the launcher. The modified straps 103 are characterized by clamping blocks 104 having trunnions 105 at one end pivotally engaged in hook-shaped bearing surfaces 106 formed at the rear ends of the straps. Thus, as the straps are brought together, the forward edges of the blocks engage the rear edges of the front sight mounting and thereby provide means for drawing the sleeve rearwardly relative to the tube and simultaneously opening the gas valve.

A modification of the launcher is shown in Fig. 13. As shown, the device comprises a substantially rectangular block 110 having a closed rectangular loop 111 at its rear end and a depending rectangular boss 112 at its front end. A threaded hole 113 is formed in the forward end of the block and immediately below the threaded hole 113 and parallel thereto is a second threaded hole 114 of considerably smaller diameter than the hole 113 formed in the boss 112. A tubular member 115 is threaded secured in the hole 113 and constitutes a grenade holder while a relatively long threaded stud 116 is secured in the hole 114 parallel to the tubular member 115.

In use, the cylindrical member 115 and thread-

ed stud 116 are backed off sufficiently to enable the loop 111 to be mounted over the front sight, the rear edge of the loop engaging the rear edge of the front sight. The tubular member 115 is then turned up so that its rear end is brought into tight abutting engagement with the muzzle of the rifle barrel. The threaded stud is then turned up sufficiently so that its end engages the valve stem and lifts it off its seat. Although no means are shown on the cylindrical member 115 for frictionally securing a grenade thereto, it will be understood that a friction ring of the type shown and described above or an equivalent type may be suitably mounted thereon.

What is claimed is:

1. A device for launching projectiles from a firearm comprising a tube; a sleeve slidable thereon; resilient means on said tube constructed and arranged to resist sliding movement of said sleeve on said tube; and means on said sleeve for fastening said tube to said barrel by sliding said sleeve on said tube against the resisting force of said resilient means.

2. A device for launching projectiles from a firearm comprising a tube having an external shoulder; a sleeve slidable on said tube and having an internal shoulder, the shoulders of said tube and sleeve being adapted to form an annular recess between said tube and sleeve; a coil spring in said annular recess engageable with the respective shoulders of said tube and sleeve to resist relative sliding movement thereof; and straps on said sleeve for fastening said tube to said barrel by sliding said sleeve relative to said tube.

3. In a firearm, the combination with a barrel having a front sight mounting; of a projectile launching means mounted on said barrel; means for fastening said launching means to said barrel comprising a pair of straps pivoted on opposite sides of said launching means, each strap having a hook-shaped end adapted to engage behind the front sight mounting; and a clip pivotally secured to one strap adapted to lock said straps in engagement with said front sight mounting.

4. The combination with an automatic firearm comprising a barrel having a front sight mounting; of a projectile launching device mounted on said barrel for supporting projectiles to be launched; and means on said launching device engageable with the front sight mounting to secure said launching device on said barrel, said engageable means comprising a pair of members pivotally secured on opposite sides of said launching device and having laterally extending lips arranged to overlie each other in frictionally engaged relationship and in said relationship to cammingly engage the rear edge of said front sight mounting.

5. The combination with an automatic firearm comprising a barrel having a front sight mounting; of a projectile launching device mounted on said barrel for supporting projectiles to be launched; means on said launching device engageable with the front sight mounting to secure said launching device on said barrel, said engageable means comprising a pair of members pivotally secured on opposite sides of said launching device, said members having laterally extending lips arranged to overlie each other in frictionally engaged relationship and in said relationship to cammingly engage the rear edge of said front sight mounting; and a locking device mounted on one only of said members arranged to clasp said pivoted members and lock the lips

thereof in the aforesaid frictionally engaged relationship.

6. The combination with an automatic firearm comprising a barrel; of a projectile launching device for supporting a projectile to be launched by gas pressure generated in said barrel, comprising a tube mounted on the muzzle of said barrel, a sleeve slidably mounted on said tube, means including said sleeve to resiliently secure said tube

to said barrel, and a friction ring on said launching device to releasably retain a projectile thereon, said friction ring being mounted on said sleeve and slideable on said tube to allow for movement of said sleeve relative to said tube by said resilient means.

PETER B. RUTHERFORD.
DONALD R. LUSTER.
